INVENTOR.

BY David C. Duncan.
Geo. Stevens.

ATTORNEY.

UNITED STATES PATENT OFFICE.

DAVID C. DUNCAN, OF DULUTH, MINNESOTA.

PORTABLE GAS GENERATOR.

Application filed November 24, 1919. Serial No. 340,382.

To all whom it may concern:

Be it known that I, DAVID C. DUNCAN, a citizen of the United States, residing at Duluth, in the county of St. Louis and State 5 of Minnesota, have invented certain new and useful Improvements in Portable Gas Generators, of which the following is a specification, reference being had therein to the accompanying drawing.

10 This invention consists of certain improvements in acetylene lighting devices and has special reference to novel means for preventing excess of water contacting the carbide or other substance from which the 15 gas for illumination or other purpose is generated and which forms the principal object of the invention.

A still further special application of the 20 invention is to portable gas generating devices such, for example, as flare lights which are well known and comprise an upright container in which the necessary water for generation is carried, and a vertically removable bell or gas tank supporting internally thereof the cage or holder for the carbide or "carbic cake" as the briquetted carbide is commonly called.

Such lights are moved about from place 25 to place by hand and used in many forms of work. Some of them are carried upon vehicles and it is found in such use that frequently the vibration or motion of the vehicle will cause the water in the container below the carbide to splash about and cause 30 unsatisfactory results and as before stated the principal object of my present invention is to correct such fault.

Other objects and advantages of the 35 peculiar construction herein described will appear in the further description of the invention.

In the accompanying drawings forming part of this application and in which like reference characters indicate like parts:

40 Fig. 1 is a side elevation of one of the completely assembled improved carbide holders.

Fig. 2 is a central vertical sectional view 45 through the same showing therein two cakes of solidified carbide.

Fig. 3 is a plan view of a modified form 50 of baffle for steadyng the action of the water.

Fig. 4 is a plan view of the baffles shown 55 in Fig. 2 looking down from the line 4-4, Fig. 2, and

Fig. 5 is a central vertical sectional view of a flare light tank showing the improved holder installed therein.

This holder is carried in all respects in 60 the usual manner within the gas bell of the water containing tank of the light so that I shall proceed to describe only the novel features and construction of my improved holder.

65 1 represents the outer cylindrical casing which is conically shaped at its bottom as at 2, the latter truncated as at 3 forming a circular opening having a diameter preferably substantially one-third that of the base 70 of the cone. Within the casing 1 is suspended the cylindrical holder 4 having a removable cap or cover 5 as is usual in such devices and provided with an annular extending flange 6 fixed to the side walls thereof 75 approximately midway of its ends and which flange rests upon the upper end of the casing 1 when the holder is in place within same.

About the lower end of the cylinder 4 and 80 externally thereof are fastened suitably spaced depending wire supports 7 upon the inwardly turned ends of which the carbide cakes rest, as is common, and about the upper ends of the wires 7 externally of the 85 cylinder 4 is attached a band 8 having a flaring lower edge indicated at 9 which is of a diameter somewhat less than that of the interior of the casing 1 and which acts as a guide to the holder in keeping it centrally 90 positioned therein, as well as preventing any descending condensed water coming in contact with the carbide.

95 Spaced a distance about the juncture of the straight side walls of the casing 1 with the conically shaped base 2 and securely fixed to the inside of the casing is an inwardly inclined annular or frustro conically shaped baffle 20, the lower edge of which preferably terminates on a plane with the 100 lower end of the cylindrical portion of the casing and through the walls of which latter just below its union with the baffle are series of vent holes 10 to allow the free escape of either gas or water when the latter fluctuates, as may occur.

105 Adjacent the lower edge of this baffle and preferably engaging same are two diametrically opposed straight vertical baffles 11 and 12 they crossing each other and being 110 united in any desired manner at the center. These vertical baffles extend downwardly the

full depth of the conically shaped base 2 and preferably are attached by soldering or otherwise the full length of such contact as at 13.

5 I prefer to form in these vertical baffles a plurality of holes indicated at 14, and which are found to provide the proper means of circulation for the water thereabouts and resting within the uppermost edges of the 10 vertical baffles is a circular inserted band 15 which forms an additional baffle concentric with the casing 1.

I have shown suspended from the outer 15 side walls of the casing 1 an annular rim or band 16 of equal diameter to that of the casing, by preferably four suitable strips 17 the lowermost edge of the band 16 being preferably on the same horizontal plane with the lower end of the conical termination 2 20 of the casing and which band is engaged by the usual hooks or rods for supporting the holder within the gas bell and which latter does not form part of my present invention.

25 In Fig. 3 I have illustrated a modified form of baffling spider and wherein the annular ring 15 is omitted, a straight inclined member 18 being installed within the angles intermediate of the vertical baffles 11 and 12, 30 their vertical relation being indicated in dotted lines at 19 Fig. 2.

This construction is particularly designed 35 for use in a portable generator that is subject to more or less vertical motion, the baffles 18 being formed for the purpose of preventing the water piling up centrally of the volume or pillaring and thus excessively contacting the carbide, whereas the structure shown in Figs. 2 and 4 is more particularly 40 designed for use in a machine subjected to lateral vibration.

45 From the foregoing it is evident that I have devised simple means for preventing extensive movement of the volume of water beneath the carbide holder and within the

gas bell of a machine such as referred to and also that the same may be considerably modified in construction without departing from the spirit of the invention.

Having thus described my invention what I claim and desire to secure by Letters Patent is:

1. A combined carbide holder and water-controlling device therefor, comprising a cylindrical casing surrounding the holder having a frustro conically shaped extension upon the bottom thereof below the holder, vertically disposed baffles within the extension, a concentric vertically disposed baffle within the first mentioned baffles, a frustro conically shaped baffle surrounding the lower end of the holder above the baffles, the upper end of said frustro conically shaped baffle being the full size of the inside diameter of the casing, and carried thereby, said casing having vent holes therethrough below the upper end of the frustro conically shaped baffle, substantially as and for the purpose described. 55

2. A combined carbide holder and water-controlling device therefor, comprising a cylindrical casing surrounding the holder having a frustro conically shaped extension upon the bottom thereof below the holder, vertically disposed baffles within the extension, a frustro conically shaped baffle surrounding the lower end of the holder above the vertical baffles, the upper end of said frustro conically shaped baffle being the full size of the inside diameter of the casing, said casing having vent holes therethrough below the upper end of the frustro conically shaped baffle, substantially as and for the purpose described. 75

In testimony whereof I hereunto affix my signature in the presence of two witnesses.

DAVID C. DUNCAN.
